(57) **CLAIM**

The ornamental design for a tissue ligation device as shown and described.

DESCRIPTION

FIG. 1 is an isometric view of our new design for a tissue ligation device;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a first end view of the design of FIG. 1;

FIG. 7 is a second end view of the design of FIG. 1; and,

FIG. 8 is an isometric exploded view of the design of FIG. 1.

The broken lines in the drawings illustrate portions of the tissue ligation device which form no part of the claimed design.
